SAFETY LOCK END CONNECTION

Sven O. Myrberg, Providence, R. I., assignor to
Providence Stock Company, a corporation of
Rhode Island

Application April 30, 1940, Serial No. 332,434

7 Claims. (Cl. 24—265)

My present invention relates to end connections, and has particular reference to end connections for cord bracelets such as wrist watch straps.

It is the principal object of my invention to provide an end connection for releasably receiving the ends of a cord bracelet.

It is a further object of my invention to provide an end connection which securely locks a bracelet end, and which cannot be accidentally or inadvertently released.

It is an additional object of my invention to form an end connection from stamped metal parts, whereby the cost of manufacture is greatly lowered.

With the above and other objects and advantageous features in view, my invention consists of a novel arrangement of parts more fully disclosed in the detailed description following, in conjunction with the accompanying drawing, and more specifically defined in the claims appended thereto.

In the drawing:

Fig. 1 is a plan view of a wrist watch strap equipped with end connections embodying the novel invention;

Fig. 2 is a plan view of one end connection, the parts being in locked position;

Fig. 3 is a view similar to Fig. 2, the parts being in unlocked position;

Fig. 4 is a perspective view of the end connection;

Fig. 5 is a vertical section on the line 5—5 of Fig. 3;

Fig. 6 is a perspective view of a modified form showing the top thereof; and

Fig. 7 is a similar view showing the bottom thereof.

Referring to the drawing, the wrist watch strap has the usual two sections 10, 11 which are connected to the wrist watch, not shown, at one end, and have end connections 12, 13, detachably secured to the other end, which are locked to an extension device or center catch 14 of standard type.

The end connections are preferably similar in construction, and include a housing 15, see Fig. 4, preferably stamped of sheet metal, having a base 16 which is equipped with an upstanding integral prong 17, and sides 18 with inturned integral lugs 19, a lock top 20 being formed with pivot pins 21 which pivotally seat in openings 22 at the lower portions of the sides 18 and integral prongs 23 which cooperate with the prong 17. The back edge of the top is formed as a cam edge

22a for engaging the loose ends of a strap section, whereby the length of the strap section may be adjusted, the two ends being gripped by the prongs 17 and 23 at one end, and by the cam edge 22a at the other end; the top is reduced in width from the free end to the pivot 21, as indicated at 24, to freely pass the lugs 19 and to allow sufficient room between the side 18 for the edge of the sliding plate 26, see Fig. 3, and is provided with a finger tab 25 for facilitating lifting.

A separate plate 26 has a plurality of fingers 27, see Fig. 4, bent over to engage the lower surface of the top, whereby it is slidable over the top; the plate 26 has two raised portions 28 with a slot 29 therebetween, to facilitate insertion of a finger nail between the raised portions for sliding the plate in either direction, the sides of the plate passing under the lugs 19 when in locking position to be retained thereunder. A raised button 30, see Fig. 2, is provided on the top 24 to cooperate with the contiguous edge of the plate to releasably hold it in locking position. The forward end of the base 16 is preferably bent upwardly as indicated at 31, Fig. 5, and a slot 32 is provided adjacent the bent end 31, to receive one hook of the extension device or center catch 14; any standard form of slot or hook may be used at the forward end, to conform with the design of the bracelet or wrist watch strap, or to conform to the wrist watch construction.

If it is desired to provide the cord end with a hook instead of a slot, as for attachment to the watch, the construction illustrated in Figs. 6 and 7 may be used. Referring to these figures, the housing 33 is adapted to receive and lock the cord ends similarly to the construction hereinbefore described. However, the housing 33 is here provided with an integral extending portion 34 which locks around a U-shaped member 35 having a forwardly extending hook 36. A lock slide 37 is bent around the portions 34 and 35 and is slidable thereon. The forward end of the slide 37 is provided with an integral tab 38 which rides over the end of the hook 36 when the slide 37 is moved forwardly and locks the hook. The top of the portion 34 is provided with a button 39 for releasably retaining the slide 37 in locking position, and the slide is slotted, as at 40, to provide a finger engagement for opening and closing.

My novel invention thus includes a housing to receive the cord strap or bracelet ends, a locking top closing the housing and being retained in place by a slidable locking plate, the ends being doubly gripped by coating prongs and a cam edge, whereby a safety lock end connection is

provided. All the parts are preferably stamped from sheet metal, whereby the cost of manufacture is lowered.

While I have described a specific constructional embodiment of my invention, it is evident that changes in the materials used, in the size and shape of the parts, in the strap end engaging elements, and in the means provided for a safety lock for preventing accidental or inadvertent release of the locking top, may be made to suit the requirements for different bracelets and wrist watch strap designs, without departing from the spirit and the scope of the invention as defined in the appended claims.

I claim:

1. In an end connection, a housing having side walls, a top hingedly mounted in said walls at one end thereof, said housing and said top having cooperating strap gripping parts, said side walls having retainer lugs at the other end thereof, and locking means slidably mounted over said top and engageable with said retainer lugs, said locking means including a plate having edge portions adapted to removably seat under said lugs.

2. In an end connection, a housing having side walls, a top hingedly mounted in said walls at one end thereof, said housing and said top having cooperating strap gripping parts, said side walls having retainer lugs at the other end thereof, and locking means slidably mounted over said top and engageable with said retainer lugs, said locking means including a plate having edge portions adapted to removably seat under said lugs, said housing having a lock element for releasably retaining said plate element in locking position.

3. In an end connection, a housing having side walls, a top hingedly mounted in said walls at one end thereof, said housing and said top having cooperating strap gripping parts, said side walls having retainer lugs at the other end thereof, and locking means slidably mounted over said top and engageable with said retainer lugs, said locking means including a plate having edge portions adapted to removably seat under said

lugs, said housing having a lock button engageable with the plate end for releasably retaining said plate element in locking position.

4. In an end connection, a housing having side walls, a top hingedly mounted in said walls at one end thereof, said housing and said top having cooperating strap gripping parts, said side walls having retainer lugs at the other end thereof, and locking means slidably mounted over said top and engageable with said retainer lugs, said top being of reduced width to clear said lugs, and said locking means including a plate slidably mounted on said top and having edge portions adapted to removably seat under said lugs.

5. In an end connection, a housing having side walls, a top hingedly mounted in said walls at one end thereof, said housing and said top having cooperating strap gripping parts, said side walls having retainer lugs at the other end thereof, and locking means slidably mounted over said top and engageable with said retainer lugs, said locking means including a plate having edge portions adapted to removably seat under said lugs, said plate having finger engageable means.

6. In an end connection, a housing having side walls, a top hingedly mounted in said walls at one end thereof, said housing and said top having cooperating strap gripping parts, said side walls having retainer lugs at the other end thereof, and locking means slidably mounted over said top and engageable with said retainer lugs, said top being of reduced width to clear said lugs, and said locking means including a plate slidably mounted on said top and having edge portions adapted to removably seat under said lugs, said plate having finger engageable means.

7. In an end connection, a housing having side walls, a top hingedly mounted in said walls at one end thereof, said housing and said top having cooperating strap gripping parts, said side walls having retainer lugs at the other end thereof, and locking means slidably mounted over said top and engageable with said retainer lugs to lock said top in strap gripping position.

SVEN O. MYRBERG.
